UNITED STATES PATENT OFFICE.

EDWIN A. MEYER, OF MENASHA, WISCONSIN, ASSIGNEE, BY MESNE ASSIGNMENTS,
TO MARATHON PAPER MILLS COMPANY, OF ROTHSCHILD, WISCONSIN, A COR-
PORATION OF WISCONSIN.

ROLLED-MATERIAL-DISPENSING CARTON.

Application filed June 3, 1926. Serial No. 113,429.

This invention relates to dispensing devices for rolled material—preferably of such a character that it can be torn off into separated pieces of desired size as delivered by the device; specifically it is designed for dispensing of waxed paper for household use in wrapping articles of all sorts including food products.

The object of the invention is to provide an inexpensive paper board or the like carton in which the roll of material to be dispensed can be packed at the factory, the whole being of such a character that the material to be dispensed may be unrolled and delivered from the carton while the roll itself is under the control of the operator outside the carton, thus doing away with the difficulties which arise when the roll of material to be dispensed is allowed to uncoil itself within the carton or other container.

The invention consists in mechanism capable of attaining the foregoing and other objects; which can be easily and cheaply made; which is satisfactory in use and which is not readily liable to get out of order.

More particularly the invention consists in numerous features and details of construction which will be hereafter more fully set forth in the specification and claims.

Referring to the drawings in which like numerals designate the same parts throughout the several views:

Figure 1 is a perspective view illustrating the device of this invention in its preferred form in the actual operation of delivering waxed paper or the like therefrom.

Figure 2 is a transverse, sectional detail end view of the mechanism of Figure 1.

The carton 10 shown in the drawings includes conventional side walls 12 and 14 arising from a bottom 16 and is closed by a top flap 18 having a downwardly turnable tongue 20 conventionally entering the box adjacent to wall 14. The box, as sold, contains a roll 40 of coiled paper 22 having its free end 24 passing out of the box between wall 14 and downwardly turned tongue 20, as clearly shown in Figure 2. When the roll of paper or the like 22 has been once inserted in the box and the cover 18 closed, the cover is preferably but not necessarily permanently secured in closed position by adhesive seals 26—28 or the like.

The cover 18 and tongue 20 are provided

adjacent to wall 14 of the box with an opening 30 of sufficient size to receive a thumb 32 of one hand of the operator for the purpose of grasping the paper end 24 inside the box and pulling it out to the position of Figure 2, preparatory to turning the withdrawn part of the paper along the upper stiff and therefore cutting or turning edge 36 of box side 14.

One wall of the box, as 12, is provided with a rectangular perforation 38 through which another thumb 40 of the operator may be inserted, as shown, to press upon the exterior surface of the roll of paper or the like 22 inside the box to thereby brake or retard the rolling action of the roll of paper inside the box as the end 24 is withdrawn from it to thereby insure the roll of paper in the box 70 maintaining its normal, initial closely rolled condition. This perforation 38 is preferably but not necessarily provided with the hinged brake-cushion flap 42, preferably but not necessarily made by leaving the part of box 75 wall material which was severed in making perforation 38 hinge to the wall on one of its four sides as shown in the drawing, specifically the lower side 44.

In the operation of the device, the purchaser of the carton loaded with paper 22 manipulates thumb 40 to press flap 42 against the roll of paper 22 in the box with just sufficient frictional contact so that on manipulating thumb 32 and with it fingers 46 to withdraw paper end 24 from the box, the roll of paper in the box does not unduly unwind.

By using the mechanism of this invention, wax paper 22 or other material designed for handling food and the like, where freshness 90 and cleanliness are absolutely essential, may be dispensed in this carton without coming in contact with human hands from the time it is placed in the carton 10 in the factory until the operator withdraws and tears off a piece 95 of the desired size along cutting edge 36.

In actual practice, the device has gone into extensive use displacing other mechanisms and methods of vending papers and the like intended for use in connection with food.

With this device, only the necessary amount of paper need be torn off at a time, thus preventing wasting the waxed paper which is ordinarily done.

This device also keeps the waxed paper 105 from becoming at times crushed and wrinkled.

Also it avoids the operator's picking up and therefore wasting several sheets at a time, when only one is required.

Member 42 serves the useful function of 5 protecting the rolled material from coming into direct contact with the thumb 40 of the operator used in checking the rotation of the roll of paper 22; likewise it protects the thumb of the operator, if that protection is 10 in fact necessary.

The invention is applicable to any form of box but is especially applicable to a paper board or similar carton of the character described, produced economically by stamping 15 operations.

Having thus described my invention, what I claim as new and desire to secure by Letters Patent is:

1. A carton in the form of a box adapted 20 to contain a roll of material, said box having a slot for the discharge of material unwound from said roll, and manually operable means carried by said box frictionally engageable with said roll intermediate its ends to check 25 rotation of the roll during discharge of a portion thereof through said slot, said means being manually operable externally of the box without opening the box.

2. A carton in the form of an elongated 30 box adapted to contain a roll of material, said box having a slot for the discharge of material unwound from said roll, and further having an opening formed therein through which the user's finger may be inserted into 35 the box for effecting frictional engagement with said roll to check rotation thereof during discharge of a portion thereof through said slot, said opening being located intermediate the ends of said box thereby rendering 40 it possible to frictionally engage said roll intermediate its ends.

3. A carton in the form of an elongated 45 box adapted to contain a roll of material, said box having a slot for the discharge of material unwound from said roll and a swinging flap formed on said box manually 50 depressible into frictional engagement with said roll intermediate the ends thereof without opening said box to check its rotation during discharge of portions thereof through said slot.

4. A carton in the form of an elongated box 55 adapted to contain a roll of material including side walls and a cover, said cover terminating in a flap disposed within the box in slight spaced relation to one of said side walls to provide a slot for the discharge of material unwound from said roll, said box being provided with a single continuous opening

formed partly in said cover and partly in 60 said flap for the insertion of a finger into the box into engagement with a portion of the material disposed between said side wall and said flap to initiate discharge of the material through said slot, another of said side walls having an opening to permit the manual 65 checking of the rotation of the roll.

5. A carton in the form of an elongated box adapted to contain a roll of material, including side walls and a cover, said cover 70 terminating in a flap disposed within the box in slight spaced relation to one of said side walls to provide a slot for the discharge of material unwound from said roll, said box being provided with a single continuous opening 75 formed partly in said cover and partly in said flap for the insertion of a finger into the box into engagement with a portion of the material disposed between said side wall and said flap to initiate discharge of the material 80 through said slot, and a flap formed integral with another of said side walls and adapted to be swung inwardly to engage the periphery of the contained roll of material, thereby effectively enabling the rotation of said roll 85 to be checked.

6. A carton in the form of a box for containing a roll of material, including side walls and a cover, said cover terminating in a flap disposed within the box in slight 90 spaced relation to one of said side walls to provide a slot for the discharge of material unwound from said roll, and a flap positioned intermediate the ends of said box which is manually depressible into frictional engagement with said roll intermediate the ends thereof to check its rotation during discharge of portions thereof through said slot, said 95 carton being constructed and arranged to remain closed during the withdrawal of material therefrom.

7. A carton in the form of a box for retaining a roll of material, including side walls and a cover, a slot being presented adjacent one of said side walls for the discharge of 100 material unwound from said roll, an edge of the side wall adjacent said discharge opening, providing a cutting edge by means of which the paper may be severed, and roll 105 engaging means provided intermediate the extremities of the box, said means being manually depressible into frictional engagement with said roll to check its rotation during the discharge and severing of the material.

In witness whereof, I have hereunto subscribed my name.

EDWIN A. MEYER.
